MULTIPLE KEY SWITCH

Laurens Hammond, Chicago, Ill.

Application April 24, 1936, Serial No. 76,157

19 Claims.

(Cl. 84—337)

My invention relates generally to multiple key switches, and more particularly to switches usable in electrical musical instruments.

It is an object of my invention to provide an improved multiple key switch which is simple and durable in construction, which may be easily assembled, and in which the contact points may be easily cleaned.

A further object of my invention is to provide a multiple switch assembly in which all of the parts are contained in a dust-proof housing.

A further object is to provide an improved method of wiring the terminals of the switches to soldering lugs.

15 A further object is to provide an improved multiple switch construction in which the individual contact carrying arms may be assembled in their supports without the use of tools of any kind.

20 A further object is to provide an improved switch contact for switches carrying currents of low voltage and amperage.

A further object is to provide an improved means for actuating multiple switches.

25 Other objects will appear from the following description, reference being had to the accompanying drawings, in which:

Fig. 1 is a vertical cross-sectional view of the manual and key-operated switch assembly of 30 an electric organ;

Fig. 2 is an enlarged fragmentary section taken on the line 2—2 of Fig. 1, one of the multiple key switches being shown in closed position;

Fig. 3 is a greatly enlarged fragmentary sectional view taken on the line 3—3 of Fig. 2;

Fig. 4 is in part a plan view of the manual and switch assembly, and in part a sectional view taken on the line 4—4 of Fig. 1;

Fig. 5 is a vertical sectional view taken on the 40 line 5—5 of Fig. 4 and showing the mechanism for shifting the bus bars;

Fig. 6 is a sectional view taken on the line 6—6 of Figs. 1 and 5;

Fig. 7 is a detail illustrating the method of 45 securing the contact arms or switch fingers in their mounting plates; and

Fig. 8 is a fragmentary vertical sectional view taken on the line 8—8 of Fig. 4.

50 The key switch assembly of the present invention forms a part of the electrical musical instrument which is fully disclosed in my Patent No. 1,956,350, granted April 24, 1934, to which reference may be had for a disclosure of the general construction of the instrument and of the 55

various parts used with, but not directly concerned with, the invention claimed herein.

As more fully disclosed in the aforesaid patent, alternating sine wave currents of the various frequencies of the tempered musical scale are produced by minute generators, and by means of key-operated switches, current from selected ones of these generators, corresponding to the fundamental and the various desired harmonics, are, upon the depression of a key, simultaneously introduced into the output circuit of the instrument. Inasmuch as the instrument may have sixty-one keys for each manual, and each key will operate nine switches, it will be apparent that several hundreds of switches must be provided. These switches are preferably arranged in files spaced apart by the distance between the successive keys of the standard organ manual, in order that the actuation of the switches by the keys may be readily accomplished. For this reason, the usual contact switch construction would not be suitable for use in an instrument of this character. Furthermore, due to the great number of switches present in the instrument, each switch is very simple and cheap so that the instrument may be produced at a reasonable cost.

Another desirable feature of the switches which is incorporated in the present invention is that the contacts of the switches are made of non-corrosive, non-oxidizing, non-pitting conductors. The usual cheaper contact metals are unsuitable because they do not maintain a good contact surface over extended periods of time, and it has been found that some of the rare metals, such as platinum, platinum iridium alloys, and palladium, form the most durable and efficient contacts for this type of circuit. In the present invention, due to the novel form of the contacts, the quantity of the rare and expensive contact metal necessary is reduced to a practical value so that even though there are hundreds of switches in the instrument, the cost of the rare metal necessary for over a thousand switch contacts is not excessive.

One of the difficulties formerly experienced with switches of the type usable in electrical musical instruments was that particles of dust or other foreign matter settled between the contacts of a switch and rendered the switch ineffective. Even a small particle of lint or dust located between the switch contacts will interrupt the circuit because of the extremely low voltage and amperage of the current transmitted through the switch. One of the features of the present invention is therefore the enclosure of the

switching mechanism in a substantially dust-proof compartment and the provision of means for simultaneously wiping or cleaning a plurality or all of the switch contacts. Even though the 5 switch contacts carry currents of low voltage and amperage, and thus the possibility of damage of the contact points by arcing is not present, there is mechanical wear upon the contacts, and the construction of the present invention therefore 10 provides means for easily renewing the contact points without disassembling the switch unit.

Referring to Fig. 1, the key switches are enclosed in a dust-proof compartment composed of a sheet metal L-shaped strip 10, a back plate 15 12, a bottom sheet 14, and a top sheet 16. The switch assembly is supported by a plurality of vertical compartment walls 18, the front of each of the compartments formed between the plates 18 being enclosed by a flexible wall 20. The rear 20 wall 12 is secured to the L-shaped strip 10 by cap screws 21. Vertical plates 18 have upwardly extending lugs 22 which project into complementary openings formed in the horizontal leg of the L-shaped strip or angle plate 10, and have 25 downwardly extending lugs 23 near their forward ends which project into apertures formed in the horizontal portion of an angle strip 24 which extends the full length of the manual.

The plates 18 are secured to the angle strips 30 10 and 24 by cap screws 26 and 28 respectively. The cap screws 26 are threaded through strips 30 which extend the full length of the manual, projecting through apertures 32 formed in the plates 18. The cap screws 28 are threaded in a 35 long strip 34 which overlies the tops of the forward ends of the vertical plates 18, resting in a recess 36 formed in the plates 18. The top sheet 16 is secured to the vertical plates 18 by cap screws 38 which are threaded in a strip 40 extending the full length of the manual and projecting through apertures 42 formed in the plates. The rearward edge of the top sheet 16 is bent upwardly as indicated at 44 and compresses a felt strip 46 against the lower face of 45 the forward edge of the angle strip 10, thus preventing the admission of dust at the joint between the sheet 16 and angle strip 10. The bottom sheet 14 is secured to the vertical frame plates 18 by cap screws 48 and 50 which are threaded in strips 52 and 54 respectively, these strips projecting through apertures 56 and 58 respectively formed in the vertical plates 18. The space between the rearward edge of the lower sheet 14 and the rear sheet 16 is sealed by a felt strip 60, 55 and similar felt strips 62 and 64 seal the upper and lower edges respectively of the front compartment walls 20. These walls have forwardly extending flanges 66 at their ends, said flanges containing perforations 68. As best shown in 60 Fig. 4, wires 70 extending the full length of the manual are threaded through the perforations 68 and complementary perforations formed in the vertical plates 18, and thus hold the walls 20 in position.

65 In addition to being properly spaced by the lugs 22 and 23, the vertical plates 18 are spaced by strips 72, 74, and 76. These strips are each provided with notches 77 in one edge thereof, the notches being of sufficient width to receive the 70 plates 18. After sliding the strips 72, 74, and 76 through the complementary shaped apertures formed therefor in the vertical plates 18, the strips are moved laterally to bring their notches into intermeshing engagement with the plates, 75 and the strips held in this position by pairs of

wires 78. It will thus be apparent that the vertical plates 18 are held in properly spaced relation at a plurality of points so that even though the casing for the switches is subjected to a load and deformed to some extent, the proper spacing 5 of the plates 18 will not be disturbed. The assembly as a whole is thus very flexible without sacrificing accuracy in the alignment of the various parts.

A plurality of switch mounting plates 80 and 82 made of suitable insulating material, such as a phenol condensation product, are supported by the vertical plates 18. These plates 80 and 82 may be of convenient length, extending approximately the distance between four adjacent vertical plates 18. The lower edge of the insulating plate 80 and the upper edge of the corresponding plate 82 are provided with notches of width to receive the vertical plates 18, and these notches are interengaged with the vertical plates 18 by 15 moving the insulating plate 80 downwardly and the insulating plate 82 upwardly and then inserting locking wires 84 and 86 to hold the plates in their displaced position in locking engagement with the vertical plates 18. 25

As shown in Fig. 8, the insulating plate 80 (which is substantially identical in construction with the plate 82) is provided with a plurality of polygonal apertures 88. The contact arms or switch fingers 90 project through these apertures 30 88 and are held in position by the rear plate 82, as best shown in Figs. 4 and 7. The switch fingers 90 are preferably stamped from a thin sheet of phosphor bronze, and at their rearward ends are provided with an open end slot 94 thus forming 35 a latch portion 96 and a connection portion 98. As indicated in Fig. 7, the switch fingers 90 are inserted through the apertures 88 in the insulating plates 82 and 80 until the latch portion 96 is bent inwardly because of the engagement of 40 its cam surface 100 with the edge of the aperture 88, whereupon the notch 102 formed in the latch portion 96 will spring into engagement with the insulating plate 82, as indicated in the upper portion of Fig. 7, thus securely latching the 45 contact finger against longitudinal movement relative to the insulating plates 80 and 82. The forward ends of the switch fingers 90 have a narrow tip 104, to the lower surface of which is welded a short length of wire 106 which is preferably made of a palladium alloy, but may be made of platinum, a platinum iridium alloy, or similar non-corrosive, non-oxidizing metal. The wire is preferably, for the sake of economy, of extremely small diameter, in the order of .007" in 50 diameter. It is found that a contact made of this wire will be effective to make a good connection throughout the useful life of the instrument. 55

The switch fingers are normally slightly bowed, as indicated in Fig. 1, with their forward tips 104 abutting against insulating strips 108 which extend the full length of the manual, and are threaded through suitable apertures formed in insulating bus bar supports 110. As will be apparent from Fig. 4, bus bar supports 110 are 60 located between successive pairs of files of switch fingers 90, and are supported by a pair of rods 112 which extend the length of the manual and are threaded through complementary holes in the bus bar supports 110 and in the vertical plates 18. 65 The bus bar supports 110 are suitably spaced by the notched strip 76, this strip having notches to engage the bus bar supports as well as notches for engagement with the vertical plates 18. The bus bar supports 110 are provided with generally 70 75

L-shaped openings 114, the horizontal portions of which receive the insulating strips 108 and the vertical portions of which receive bus bars 116. (It will be noted that the uppermost insulating strip 108 merely forms an upper limit stop for the switch finger and does not support a bus bar.)

The bus bars 116 extend the full length of the manual and rest upon the insulating strips 108 and are guided for longitudinal movement in the vertical portions of the L-shaped slots 114. The bus bars are preferably made of nickel alloy and have a wire 118 of palladium or other suitable metal welded or otherwise suitably secured thereto. In the preferred construction, the wire 118 is spot welded to the bus bar 116 at short intervals along the length of the wire. This wire is preferably softer than the wires 106 used on the switch fingers in order that if wear takes place between them, the bus bar contact wire 20 shall wear substantially to the exclusion of wear on the contact wires 106.

The switch fingers 90 are flexed so as to bring their contact wires 106 into electrical contact with the contact wires 108 of the bus bars 116 by means of actuators 120, which, as shown in Fig. 2, are provided with apertures 122 through which the switch fingers 90 project. The actuators 120 abut shoulders 124 formed on the switch fingers 90 and are held against movement away from the shoulders 124 by a block 126 of insulating material which projects through apertures 128 formed in all of the switch fingers 90 except the uppermost and lowermost fingers of a tier. The insulating block 126 thus rests upon the lowermost switch finger 90 and is held against removal by the uppermost of the switch fingers.

The upper ends of the actuators 120 are of reduced width, and project through suitable slots formed in the top sheet 16 of the switch compartment and through a thin sheet of felt 130 which is secured to the top sheet 16 by metallic strips 132 which may be riveted or otherwise suitably secured to the top sheet 16.

Inasmuch as the construction of the manual, that is, the construction of the keys and supports therefor, is more fully described and is claimed in my copending application, Serial No. 91,283, filed July 18, 1936, the construction and operation of these parts will be but briefly described herein.

Keys 134, 136 molded of a suitable plastic composition are secured to key stems in the form of metallic channels 138 which are supported on studs 140 and rest upon a fulcrum rod 142. The 55 studs 140 are riveted to the horizontal leg portion of the angle strip 10 and at their upper ends are of reduced diameter and are threaded to receive adjusting nuts 144 by which the degree of compression of coil springs 146 which surround the studs 140 may be regulated. A grooved wooden strip 148 may be placed over the row of adjusting nuts 144 to prevent the accidental loosening thereof.

Each of the channels 138 has a felt pad 150 suitably secured thereto for providing a noiseless contact with the upper end of its associated actuator 120. Upward movement of the forward ends of the white keys 134 is limited by a felt strip 152 secured to the lower surface of the inwardly extending flange 154 of an angle strip 156 which is secured to the angle 24. The felt strip 152 is engaged by an integrally molded projection 158 formed at the forward end of each of the keys 134. Downward movement of the keys 134 is limited by a heavy felt pad 160 which rests

upon and may be secured to the strip 34. Each of the black keys 136 is secured to the channel 138 by a pair of cap screws 162, 164 which are screwed into suitable threaded sockets molded into the body of the key 136. Both the white keys 134 and the black keys 136 are guided against lateral shifting movement by fabric pads 166 which are secured to the upwardly extending teeth 168 of a comb 170 by U-shaped clips 172. The comb 170 has its horizontal flange portion 174 which is secured in place by cap screws 176 projecting through the lower sheet 14. Downward movement of the keys is limited by a felt strip 177 which is held in position by pins 178 which are riveted to the flange 174.

Upward movement of the black keys 136 is limited by a felt pad 180, which is secured by a prong 182 forming part of a clip 184, the latter being secured between the channel 130 and the body of key 136 by the cap screw 162.

As previously intimated, the bus bars 116 are longitudinally slidable relative to the bus bar supports 110. As best shown in Figs. 4 and 5, the ends of the bus bars 116 are bent over and the ends clamped between a pair of insulating plates 186 and 188 by a pair of cap screws 190. The insulating plate 186 is riveted to one arm 192 of a bell crank lever 194 pivoted upon a pin 196 supported in a bracket 198. The bracket 198 may be secured to the leftmost vertical plate 18 by a pair of cap screws 200. The other arm 202 of the bell crank 194 has an open end slot in the form of a yoke embracing the reduced diameter portion 204 of a spindle 206. The spindle 206 has a threaded portion 208 screwed into an internally threaded block 210 supported by the leftmost vertical plate 18. The portion 208 is threaded into a kerfed shank 212, being secured against unscrewing by a pin 214 extending diametrically through the shank 212 and the threaded portion 208. The shank 212 extends through an aperture 216 formed in the rear sheet 12, a suitable washer 218 made of phenol condensation product or similar material being held by a compression coil spring 22 in position to seal the opening 216 against the admission of dust. The inner end of the spring 220 abuts against a washer 222 which in turn abuts against the projecting ends of the pin 214. The spring 220 not only holds the washer 218 in place, but exerts a longitudinal pressure upon the threaded portion 208 of the spindle so as to increase the friction and prevent undesired rotation of the spindle due to vibration.

As will be noted from Figs. 4 and 7, each of the projections 98 of the switch fingers 90 has an insulated German silver resistance wire 224 welded thereto. These wires 224, one from each of the switch fingers 90, are led through notches 226 formed in an insulating strip 228 clamped between a metallic channel 230 and the bottom sheet 14 by the cap screw 48. The wires are then led over a fiber or other suitable insulating sheet 232, which is held in spaced position by a tube 234 of insulating material. A metallic channel 236 is clamped to the bottom sheet 14 by cap screws 50, and this channel, as well as the two arms of the channel 230, carry notched combs 238, 240, and 242 of insulating material. The wires 224 in addition to forming an electrical connection between the switch fingers 90 and the generators form an important part of the electrical circuit of the instrument by providing a predetermined high impedance path for the flow of the current from the generators to the output 75

circuit. To obtain the predetermined resistance in the wires 224, they are measured to a certain length (approximately a yard long). If means were not provided to mount these hundreds of 5 long wires, they would become tangled and snarled and the combs 238, 240, and 242 are therefore provided as a means to support the excess 10 length of the insulated resistance wires 224. As will be noted from Fig. 6, one end of each of the 15 resistance wires 224 is soldered to a soldering lug 244, a plurality of which are riveted to an insulating strip 246 riveted to the channel 236. The intermediate length of wire is strung back and forth between the appropriate slots in the combs 20 238, 240 and 242 so that the wire will be taut 25 throughout its length. It will be understood that a plurality of wires 224 will be connected to one of the soldering lugs 244 and that these wires, although of the same length, must be connected to different tiers of switch fingers. 30 Wires 254 connect the soldering lugs 244 to the generators. (The particular connections necessary are fully disclosed in the above mentioned Patent No. 1,956,350.) The wires 224 strung up on the combs 238, 240 and 242 are covered by a horizontal extension 248 of the rear sheet 12, the horizontal extension being secured to the bottom sheet 14 by screws 250 threaded in suitable 35 spacing studs 252.

30 It is believed that the operation of the key switches will have been apparent from the preceding detailed description of their construction. Briefly, upon depression of one of the keys 134 or 136, the channel stem 138 thereof will, in swinging downwardly, engage the upper end of the associated actuator 120. The actuator will thereupon flex downwardly all of the switch fingers 90 of a vertical tier or file until the contact wires 106 of the switch fingers are firmly pressed 40 against the contact wires 118 of the bus bars 116, completing the circuit from the generators (which are connected by wires 254 to the soldering lugs 244) to the output circuit which is connected to the bus bars 116. Upon release of pressure upon 45 the depressed key, the compression spring 146 will swing the forward end of the key upwardly, whereupon the switch fingers 90 will, due to their resiliency, resume the position in which they are shown in Fig. 1, where their tip portions 50 104 are arrested by engagement with the insulating strips 108.

If, after a long period of use, some of the 55 switches should fail to make contact, the portion of the contact wires 118 which is engaged with the contact wire 106 on the switch fingers, may be shifted so as no longer to be in registry with the contact wires 106. This is accomplished by turning the shank 212 of the spindle 206 and thus 60 through the bell crank 194 pushing or pulling the bus bars 116 in one direction or the other. Inasmuch as the contact wires 106 are of exceedingly small diameter, a slight longitudinal movement of the bus bars will result in bringing new 65 portions of the bus contact wires 118 in registry with the contacts 106 of the switch fingers. Since the contact wires 106 flex as their contacts 106 are brought into contacting engagement with the bus contacting wires 118, there will be a very 70 slight wiping action, assuring a good contact. This wiping action results, however, in slight mechanical wear of the bus contact wire 118 since it is softer than the contact wire 106 and it is for this reason that the latter wire may, if desired, 75 be made of slightly greater diameter than

the contact wire 106. By substantially concentrating any mechanical wearing of the contact wires upon the bus contact wire 118, it is possible easily to compensate for such wear by shifting 5 the bus bars.

In the event that one of the switch contacts becomes defective due to the adhesion of a particle of lint or dust, such particles may usually be very easily removed by depressing the key 10 controlling the switch having the defective contact, and while holding the key depressed shifting the bus bars back and forth by rotation of the spindle shank 212. If desired, all of the 15 switch contacts may be simultaneously cleaned by holding all of the keys depressed and shifting the bus bars back and forth.

From the above description, it will be noted that the manual and the key switches form a unit which is electrically connected to the instrument by many less wires than there are separate key-actuated switch circuits. Thus in the event of damage to the manual of an instrument, it may be easily removed for repair or replacement. Furthermore, this construction lends it 25 self very advantageously to production of the instrument in large quantities at low cost.

It will be noted that the assembly of the switch fingers 90 in their supporting plates 80 and 82 and their connection with the actuator 120 is 30 easily accomplished, since it is necessary merely to slide these fingers through the apertures 88 in the plates 80 and 82 and through the apertures 122 in the actuators 120 and to drop the insulating block 126 in position just prior to inserting the uppermost of a tier of switch fingers 90.

The construction is such that although there are several hundred switches, the assembly of them is very compact, with the result that the switches of each tier may be located directly beneath, or in the plane of, the key used to actuate them, and despite the large number of switches required, the cost of the switch assembly is relatively small.

While I have shown and described a preferred 45 embodiment of my invention, it will be readily understood by those skilled in the art that variations may be made in the construction disclosed without departing from the basic features of my invention. I therefore do not wish to be limited to the precise construction disclosed, but 50 wish to include within the scope of my invention all such equivalent modifications and variations which will readily suggest themselves to those skilled in the art.

What I claim as new and desire to secure by Letters Patent of the United States is:

1. In an electrical musical instrument, the combination of a manual composed of a plurality of keys, a bank of switch fingers for each key, said banks of switch fingers being arranged in planes each in substantial alignment with its associated key, a plurality of bus bars extending in a direction perpendicular to the planes of said banks of switch fingers and each bus bar being located in a position to be contacted by one of the switch fingers of each bank, and an actuator for each bank of said switch fingers operable by the associated key to move the switch fingers into engagement with said bus bars respectively.

2. In an electrical musical instrument, the combination of a manual composed of a plurality of keys, a bank of switch fingers for each key, said banks of switch fingers being arranged

- in planes each in substantial alignment with its associated key, a plurality of bus bars extending in a direction perpendicular to the planes of said banks of switch fingers and each bus bar being located in a position to have a portion thereof contacted by one of the switch fingers of each bank, actuators individual to each bank of said switch fingers and operable by said keys respectively, and manually operable means to 5 simultaneously shift all of said bus bars longitudinally thereby to bring different portions thereof into position to be contacted by said switch fingers.
3. In an electrical musical instrument, the combination of a manual composed of a plurality of keys, a bank of switch fingers for each key, said banks of switch fingers being arranged in planes each in substantial alignment with its associated key, a plurality of bus bars extending in a direction perpendicular to the planes of said banks of switch fingers and each bus bar being located in a position to be contacted by one of the switch fingers of each bank, an actuator for each bank of said switch fingers operable by the associated key to move the switch fingers into engagement with said bus bars respectively, and means to shift said bus bars longitudinally.
4. In an electrical musical instrument, the combination of a plurality of conductors, each connected to a source of alternating current, key-operated switches for selectively connecting said conductors to an output circuit, a housing for said switches, resistance wires connecting said conductors with said switches, and a plurality of combs mounted on said housing and forming supports for stringing said wires.
5. In a multiple switch, a pair of spaced plates of insulating material having similar rows and files of perforations formed therein, a plurality of movable switch fingers extending through said perforations and each having a part engaging one of said plates detachably to hold the switch finger against longitudinal movement with respect to said plates, fixed contacts for said switch fingers, and an actuator having parts engaging each of the switch fingers of a file and operable to flex the latter into contact with said fixed contacts.
6. In an electrical musical instrument, the combination of a plurality of conductors, each connected to a source of alternating current, key-operated switches for selectively connecting said conductors to an output circuit, relatively long wires of predetermined impedance connecting said conductors with said switches, and a plurality of notched insulating strips fixed with respect to said switches and forming supports for stringing said wires.
7. A switch finger comprising a thin strip of resilient metal having a latching part cooperable with a support detachably to hold the finger against longitudinal movement relative to the support.
8. In an electrical musical instrument the combination of a plurality of similar tiers of switch fingers located in a row, a plurality of perforated bus bar supports of insulating material, a plurality of bus bars mounted for sliding movement through the perforations in said supports and located in positions to be contacted by said switch fingers, an insulating strip located beneath each of said bus bars and forming a limit stop for said switch fingers, means to move a tier of switch fingers from engagement with
- said insulating strips into contact with said bus bars respectively, and means to move said bus bars longitudinally.
9. In an electrical musical instrument the combination of a plurality of similar tiers of switch fingers located in a row, a plurality of perforated bus bar supports of insulating material, a plurality of bus bars mounted in said supports and located in positions to be contacted by said switch fingers, an insulating strip located beneath each of said bus bars and forming a limit stop for said switch fingers, and means to move a tier of switch fingers from engagement with said insulating strips into contact with said bus bars respectively.
10. A switch for electrical currents of low voltage and amperage comprising a movable switch finger having a short length of contact wire secured thereto, and a second relatively fixed contact wire extending at an appreciable angle with respect to said first named contact wire and co-operable therewith to complete an electrical circuit, said wires being in the order of .007 inch in diameter.
11. A switch for electrical currents of low voltage and amperage comprising a movable switch finger having a short length of contact wire secured thereto, a second relatively fixed contact wire extending at an appreciable angle with respect to said first named contact wire and co-operable therewith to complete an electrical circuit, said wires being in the order of .007 inch in diameter, and means to shift one of said contact wires longitudinally to bring a different portion thereof into co-operable contacting relationship with the other of said wires.
12. In a multiple switch assembly, the combination of a plurality of spaced switch finger supporting plates each having a plurality of perforations therein substantially aligned with the perforations in the other, switch fingers having apertures and shoulders and extending through aligned perforations in said supporting plates, cooperating means on said fingers and one of said plates for holding said fingers against longitudinal movement with respect to said plates, an actuator embracing a plurality of said fingers and abutting the shoulders thereon, and a block of insulating material extending through the perforations in said fingers and operable to prevent appreciable movement of said actuator in a direction away from the shoulders on said fingers.
13. In an electrical musical instrument, a unitary manual and switch assembly, comprising a plurality of keys, a plurality of switches operable by said keys, terminals mounted on said assembly for connection to different electrical generators, and a plurality of wires each having one end connected to one of said terminals and their other ends connected to different ones of said switches, whereby the assembly may be disconnected from said generators without disconnecting said wires.
14. In an electrical musical instrument, the combination of a manual assembly comprising a plurality of keys, a plurality of switches associated with and operable by each key, a plurality of terminals mounted on said manual assembly, and a plurality of wires connecting said switches with said terminals, there being only one of said wires connected at one end to each of said switches, and a plurality of said wires connected at their other ends to a single one of said terminals, whereby connection of a single conductor to one of said terminals may be effective to supply current to a plurality of said switches.

15. A switch assembly for electrical currents of low voltage and amperage comprising a plurality of movable switch members, each having a short length of contact wire secured thereto, a bus element common to a plurality of said switch members and having a contact wire secured thereto in electrical conducting relationship, said bus contact wire extending at an appreciable angle with respect to said switch contact wires and being cooperable therewith to complete electrical circuits, and means to shift said bus element with respect to said switch members thereby to make possible the cleaning of said contact wires by a rubbing action.

16. In an electrical musical instrument the combination of a plurality of switches each comprising a pair of cooperable contacts, one of the contacts being normally stationary and the other movable into engagement therewith, and means for simultaneously moving the normally stationary one of each pair of said contacts with respect to the other of the pair, thereby to clean the contacts by a rubbing action or to cause one of the contacts of each pair to engage the other at a point spaced from the original point of contact.

17. In a multiple switch assembly for currents of low voltage and amperage, a row of switch members, a bus bar of a base metal positioned adjacent said members, a contact wire of a precious

contact metal secured to said bus bar in electrical conducting relationship therewith, and means selectively to move said switch members into contact with said contact wire.

18. In a multiple switch assembly for currents of low voltage and amperage, a row of switch members, each having a contact wire of precious contact metal secured thereto, a bus bar of a base metal positioned adjacent said members, a contact wire of precious metal secured to said bus bar in electrical conducting relationship therewith and extending at an appreciable angle with respect to the contact wires of said switch members, means selectively to move the contact wires of said switch members into contact with the contact wire of said bus bar, and a manually operable means to shift said bus bar with respect to said switch members to change the points of contact between its contact wire and the contact wires of said switch members.

19. As an article of manufacture, a switch finger comprising a thin strip of resilient metal having a support-engaging notch formed in a side edge adjacent one end thereof and having a slot extending longitudinally of the strip at said end, whereby the portion of the strip near said notch will easily flex to permit disengagement of the notch from a support.
